EYECUP

Edward J. Leonard, Derby, Conn.

Application April 16, 1941, Serial No. 388,743

3 Claims. (Cl. 128—249)

This invention relates to an eye cup, and has for an object to provide an eye cup for individual use so that it may be kept sanitary, including an outer container or support of metal or some molded material which is relatively rigid and an inner cup of paper or other suitable material which is much less rigid, or more or less flexible, to be supported by the container and to be discarded after use.

It is also an object to provide a construction in which a wall of the cup or insert can be compressed or flexed to force the solution in the cup into the eye to cause a certain amount of circulation or movement of the solution or medicament to give a better cleaning and medicinal effect.

With the foregoing and other objects in view I have devised the construction illustrated in the accompanying drawing forming a part of this specification. It is, however, to be understood that I am not limited to the specific details and arrangement shown, but may employ various changes and modifications within the scope of the invention.

In this drawing:

Fig. 1 is a side elevation of the cup complete with parts broken away to more clearly show the construction;

Fig. 2 is a top plan view thereof;

Fig. 3 is a transverse vertical section thereof; and

Fig. 4 is a side elevation of the outer container looking from the opposite side of Fig. 1 and from the right of Fig. 3.

My improved eye cup comprises an outer container or support 5 of metal or some molded material, such for example as the moldable plastics which are now generally available on the market, and an inner or insert cup 6, preferably of paper or similar material. The cup 6 while sufficiently stiff to retain the solution, is also sufficiently flexible to be compressed or flexed to force the solution into the eye and cause a certain amount of circulation or movement of the solution in the eye to give a better cleaning and medicinal effect. The paper insert cup if used alone would not be sufficiently stiff or rigid to be pressed and held against the surface of the skin about the eye sufficiently tight to retain the liquid or keep it from leaking out. It would also soon soften up, rendering it still less capable of maintaining the tight fit, with the result that the solution would be apt to be spilled over the user's clothes and also cause loss of liquid. However with the combination the paper cup insert is

seated in the cavity in the similarly shaped outer container 5, and the sides of the cup 6 are carried above the top edge 7 of the container or support, but the side walls of the container are carried high enough to support the sides of the cup, and particularly to support them adjacent the rim of the cup so that the orbit conforming rim or edges 8 of the cup can be pressed and held against the surfaces of the skin about the eye to maintain a tight fit during the use of the cup.

However the top edge 7 of the container need not be so nearly conforming as is the edge or rim 8 of the cup, but the opposite end portions 9 are preferably carried higher or nearer to the rim 8 of the cup than are the intermediate or side portions 10 so as to give greater support at the opposite ends of the cup where there is the greater pressure on the edges or the rim of the cup due to the adjacent bony portions about the eye socket than at the intermediate side portions. The rim or the edge of the cup is folded or rolled over as indicated to provide greater strength or stiffness, and also to increase the width of the contacting surface on the skin to prevent injury or cutting of the skin. The rim 7 of the container may also be rolled over to give greater strength and stiffness and better support the sides of the cup.

To permit forcing of the liquid into the eye and to cause movement or circulation of this liquid one wall of the container 5, preferably one of the side walls, is provided with an opening 11 for insertion of a thumb or finger of the user. As shown in Fig. 3 a thumb 12 is shown pressed against a side wall of the cup 6, and it will be evident that by pressing this side wall inwardly, which action is permitted by the flexibility of the cup, the liquid in the cup may be forced into the eye, and also by inward and outward movement of the wall of the cup, liquid by the resulting kneading or pumping motion of the cup is forced against the cornea and eyelids, giving a certain amount of motion and circulation to this liquid. As previously noted, during this action the cup is supported by the rigid container and support 5, and during the irrigation of the parts of the orbit with which the liquid is in contact it maintains a tight contact about the rim of the cup preventing leakage or loss of liquid.

The effect of the solution is also enhanced by the pressure and the movement or circulation. The arrangement and shape of the container besides supporting the cup affords a good grip on the container during the action on the cup, and this may be improved by providing one or more de-

pressions or recesses 13 in the side wall of the container opposite that having the opening 11 to form seats for the ends of one or more fingers of the hand. Thus pressure of the thumb on the cup creates pressure on the liquid contents affording a more thorough irrigation of the cornea, lids and other parts of the orbital tissues. After use the paper cup or cup of other suitable material, is thrown away, maintaining the container sanitary for use by others.

Having thus set forth the nature of my invention what I claim is:

1. An eye cup comprising a paper insert cup having a flexible rim curved to fit the orbit of the eye of the user, and an outer container and support for the cup of the same general shape to receive and hold the cup and having side walls at the outer sides of the cup extending to a position adjacent to but spaced from the edges of the cup to support them when pressed against the surface of the skin about the eye.

2. An eye cup comprising a flexible insert cup having a rim curved to fit the orbit of the eye of the user, and an outer more rigid container

and support to receive and hold the cup having supporting side walls extending to a position spaced below but adjacent the rim of the cup to support said rim when pressed against the surface of the skin about the eye, and one of the walls of the container having an opening for passage of the thumb or a finger of the user to compress a wall of the cup to circulate liquid into the eye.

3. An eye cup comprising a paper insert cup having a flexible rim curved to fit the orbit of the eye of the user, an outer more rigid container and support for the cup having a cavity for the cup to seat in, and side walls extending to a position spaced below but adjacent the rim of the cup to support the cup when pressed against the surface of the skin about the eye, and one of the side walls of the container having a depression in its outer surface forming a finger grip and the opposite side wall having an opening permitting entrance of a thumb of the user to press inwardly a wall of the cup to force and circulate liquid from the cup into the eye.

EDWARD J. LEONARD.
